UNITED STATES PATENT OFFICE.

WILLIAM BECKEL, OF ESTEVEN, SASKATCHEWAN, CANADA, AND JOHN J. ABEL, OF PORTAL, NORTH DAKOTA.

RAIL-JOINT.

No. 865,990.

Specification of Letters Patent.

Patented Sept. 17, 1907.

Application filed June 9, 1906. Serial No. 321,076.

To all whom it may concern:

Be it known that we, WILLIAM BECKEL, a citizen of the United States, residing at Esteven, in the District of Saskatchewan, Dominion of Canada, and JOHN J. ABEL, a citizen of the United States, residing at Portal, in the county of Ward and State of North Dakota, have invented certain new and useful Improvements in Rail Joints, of which the following is a specification.

Our invention relates to rail joints, and its primary object is to provide a novel and highly useful device of this character wherein the rail ends are interlocked to prevent sagging and thus avoid the pounding incident to sagging joints, and wherein the heads of the rails are united to form a practically continuous tread 10 and thus avoid the pounding incident to the wheels of a train passing over the space usually existing between rail ends.

A further object of the invention is to provide a rail joint which is simple, one which will permit the rails 20 to be assembled easily and quickly and one wherein the cost of the manufacture of the rails is not materially increased.

With the above and other objects in view, the invention consists in the construction, combination and arrangement of parts hereinafter fully described, claimed and illustrated in the accompanying drawings, wherein:

Figure 1 is a top plan view showing our improved rail joint. Fig. 2 is a view in side elevation thereof. 30 Fig. 3 is a perspective view of one of the ends of the rail, and Fig. 4 is a transverse sectional view on the line 4—4 of Fig. 2.

Referring to the drawings by reference numerals, 1 designates the base, 2 the web and 3 the head of the 35 rail. The ends of the web 2 are thickened co-extensively with the width of the head 3, and the thickened portions of the web extend from the ends of the rails a suitable distance inwardly. Each end of the rail is cut away to provide an offset extension or tongue 40 4 and a longitudinally extending recess or seat 5, said extension or tongue 4 forming a portion of the thickened end of the web 2, thus permitting the same to be offset laterally, while the recess or seat 5 is located in the thickened end of the web 2 and of a height and 45 depth co-extensive with the width and height of the extension or tongue 4 to wholly receive the extension or tongue 4 of the next adjacent rail. The application of the extensions or tongues in the recesses or seats prevents the sagging of the rails at their joints, and thus 50 obviates the pounding incident to sagging joints. The head 3 and that portion of the web 2 lying be-

neath the extension or tongue 4 are cut away to arrange the ends of the web 2 and head 3 on a diagonal line, as indicated at 6 in the drawings. The diagonal ends 6 do not extend throughout the entire width of 55 the head 3 and web 2, but begin and terminate so as to provide flattened ends 7 and shoulders 8. When the rails are assembled, the diagonal ends fit one against the other, while the flattened ends 7 of one rail abut against the shoulders 8 of the other rail, thus providing a practically continuous tread which 60 obviates pounding incident to the wheels of a train passing over a space usually existing between the meeting ends of rails. The base 1 is removed on a line extending transversely of the rail to provide a 65 forwardly projecting extension 9 forming an integral part of the thickened portion of the web 2. This thickened portion of each rail is adapted to rest upon a shoulder 10 formed by cutting the thickened end of the web 2 on a diagonal line, as fully shown in Fig. 3 70 of the drawings. After the rails have been assembled, the same are prevented from having relative lateral movement by means of bolts 11 and nuts 12, said bolts fitting within the elongated openings 13 in the extension or tongue 4 and the thickened end of the web 2. 75

It should be apparent from the above description, taken in connection with the accompanying drawings, that we provide a rail joint wherein the ends of the rails are prevented from sagging and wherein a practically continuous tread is formed, thus obviating the 80 pounding incident to the wheels of a train passing over a sagging joint or a space usually existing between the meeting ends of rails.

It should also be apparent that we have provided a rail joint which does not materially increase the cost 85 of the manufacture of the rails, and which is simple, durable and efficient.

Having fully described and illustrated our invention, what we claim is:

A rail joint having the ends of its web thickened and cut 90 away to provide an offset extension and a recess, the ends of the head and the remaining portions of the web being cut away on a diagonal line, the ends of the base being cut away on a line extending transversely of the rail to provide an extension forming an integral portion of the web, 95 and a shoulder.

In testimony whereof, I affix my signature in presence 90 of two witnesses.

WILLIAM BECKEL.
JOHN J. ABEL.
